AUTOMATIC ADVERTISING DISPLAY DEVICE

Charles L. Murray, Waco, Tex.

Application July 16, 1934, Serial No. 735,454

4 Claims. (Cl. 40—130)

This invention relates to an automatic advertising display device for use in connection with coolers and refrigerators for bottled goods, ice-boxes, and other cabinets.

5 The primary object of the present invention is to provide a device of the above character embodying an electric advertising display sign adapted to be mounted within the cabinet and to be automatically rendered operative for displaying advertising matter to customers when the cover or door of the cabinet is raised or opened for access to the bottled goods or other articles therein.

In carrying out the present invention, the 15 illuminated display sign is provided with a top wall having a light pervious display member or sign and inclined in a forward and downward direction to clearly present the advertising or display matter to the customer when illuminated, 20 and the light source of the display sign is controlled by a switch located inside the cabinet and automatically operated to close the circuit of the light source when the cover or door of the cabinet is opened and to open said circuit when 25 said cover or door is closed. Further, the display sign is open at the bottom so that the light source of said sign will illuminate the goods in the cabinet to facilitate proper selection of the goods to be dispensed or sold, in addition to illuminating the display member of the sign.

A further object of the invention is to provide an automatic advertising display device of the above kind which is extremely simple in construction, efficient in use, inexpensive to manufacture, 30 and easy to install.

Other objects and features of the invention will become apparent from the following description when considered in connection with the accompanying drawing, and the invention consists in the novel form, combination and arrangement of parts herein illustrated, described and 35 claimed.

In the drawing:

Figure 1 is a fragmentary vertical section of a 45 cooler or refrigerator for bottled goods equipped with an advertising display device constructed in accordance with the present invention, said device being in front elevation.

Figure 2 is a fragmentary vertical section on 50 the plane of line 2—2 of Figure 1.

Figure 3 is a central vertical section of the display device per se; and

Figure 4 is a plan view of the sheet metal blank 55 employed in constructing the device of Figures 1 to 3 inclusive.

Referring in detail to the drawing, 5 indicates the open top body of an ordinary cabinet for the cooling and dispensing of bottled or other goods, said body having a hinged cover or door 6 which, when raised or opened, permits access to be had to the bottled or other goods cooled within and to be dispensed from the body 5.

The present invention includes an illuminated advertising display sign adapted to be mounted within the body 5 of the cabinet against and adjacent the upper edge of a vertical wall of the latter, said display sign including a metallic frame constructed from a blank of the form shown in Figure 4 and composed of a flat rear wall 7, a top wall 8 having a large central opening 9 closed by a light pervious display or sign member 10, said top wall 8 being integral with the upper edge of the rear wall 7 and being inclined forwardly and downwardly therefrom so that the display matter of the light pervious member 10 will be clearly visible to the customer when it is illuminated and the cover or door 6 of the cabinet is opened, and side walls 11 and 11a rigidly connecting the sides of the top wall 8 with the rear wall 7. As shown, the side walls 11 and 11a are preferably in the nature of substantially triangular wings integrally formed on the inner side edges of the top wall 8 and having projecting tongues 12 and 12a passed through slots 13 and 13a of the rear wall 7 and clinched 20 against the back of the latter so as to rigidly connect the top and rear walls of the sign and to effectively brace the top wall in its proper inclined position relative to said rear wall. The light pervious display member 10 is preferably 25 slightly larger than the opening 9 in the top wall 8 and suitably held in place by a rectangular frame 14 embracing the margin of the light pervious member 10 and fastened in any suitable way to the top wall 8 and about its opening 9.

Each side wall 11 and 11a is provided with a central opening 15 in the desired one of which is rigidly mounted a lamp socket 16, and supported by this lamp socket is an electric lamp 17 arranged beneath or behind the top wall 8 in position to illuminate the light pervious member 10 thereof. It will thus be seen that the sign is of extremely simple and durable construction with the bottom thereof left open so that the lamp 17 may illuminate the goods within the body 5 of the cabinet to facilitate proper selection of the goods to be dispensed or sold from the cabinet. Integrally formed on the upper portion of the rear wall 7 are laterally projecting ears 18 to facilitate rigid fastening of the sign flatly 50 55

against the wall of the cabinet body 5 as at 19, and it is noted that the rear wall 7 extends a substantial distance below the top wall 8 and side walls 11 and 11a where it is provided in its lower portion with further openings 20 to be further secured as at 21 to the wall of the cabinet body 6. The depending lower portion of the rear wall 7 affords a mounting for a thermometer 22 below the sign proper for use in checking the 10 temperature within the cabinet body 5 so as to insure proper cooling of the goods therein. While the thermometer 22 may be mounted in any suitable way on the front face of the wall 7 below the sign proper, supporting members may be 15 stamped from the lower portion of said wall 7 for this purpose as at 23 and 24. As shown, a thermometer tube is used, and the graduations of the thermometer may be provided directly on the front face of the lower portion of rear wall 20 7 at opposite sides of the thermometer tube as at 25. It will be particularly noted that when the lamp 17 is lighted, the latter will illuminate the thermometer to facilitate reading thereof. The lamp socket 16 is placed in circuit with a 25 source of current by means of an attachment cord 27, and a switch 28 is interposed in this circuit for controlling the lighting of lamp 17. The switch 28 may be conveniently mounted on the inside of cabinet body 5 as shown, and such switch 30 which may be of any well known or preferred construction is of the type shown in my U. S. Letters Patent No. 1,964,855, dated July 3, 1934, wherein the switch is normally closed and has an actuating member 29 arranged in the path of the cabinet 35 cover or door 6 for opening the circuit of lamp 17 when said cover or door is closed.

It will thus be seen that when the switch 28 is operated to close the circuit of lamp 17 the advertising matter on the member 19 will be illuminated, while the interior of the cabinet body 5 and the thermometer 22 will also be illuminated. Consequently, when the cover or door 6 of the cabinet is opened, the advertising matter will be displayed to the customer and the goods within 40 the cabinet will be rendered clearly visible for proper selection. As soon as the proper goods have been selected and removed the cover or 45 door 6 is closed and the switch 28 is automatically operated to extinguish the lamp 17 so that conservation of current will be had when the sign is not visible.

From the foregoing description, it will be seen that the present invention provides a very simple and attractive device which effectively serves a 55 three-fold purpose, namely, the advertising of goods or products, illumination of the interior of the cabinet from which said goods or products are dispensed, and providing for ready determination of the temperature within such cabinet 60 to facilitate maintaining the proper temperature as dictated by requirements. Minor changes in the specific details of construction illustrated and described are contemplated within the spirit and scope of the invention as claimed.

65 What I claim as new is:

1. In an automatic advertising display device of the character described, a display sign including a casing having a flat vertical rear wall and a top wall inclined forwardly and downwardly from the upper edge of said rear wall and provided with a light pervious display member, a light source within said sign casing arranged to illuminate said light pervious display member, 70 means to facilitate rigid mounting of the display

sign within a bottled goods cooling and dispensing or other refrigerating cabinet, said sign casing being open at the bottom whereby said light source may illuminate the interior of said cabinet, said rear wall of the sign casing depending below the open bottom of the latter, and a thermometer mounted on the depending lower portion of said rear wall for indicating the temperature within the cabinet and in position to also be illuminated by said light source.

2. In an automatic advertising display device of the character described, a display sign including a casing composed of a flat vertical rear wall, a forwardly and downwardly inclined top wall integral with the upper edge of said rear wall, and side walls integral with the sides of said front wall and rigidly connected to said rear wall, said top wall having a large central opening, a light pervious display member closing said opening of the top wall, a lamp socket supported by one of said side walls, a lamp carried by said socket and arranged within the sign casing to illuminate said light pervious display member, means to facilitate rigid fastening of the sign casing within a bottled goods cooling and dispensing or like cabinet, said sign casing being open at the bottom to permit the lamp to illuminate the interior of said cabinet.

3. In an automatic advertising display device of the character described, a display sign including a casing composed of a flat vertical rear wall, a forwardly and downwardly inclined top wall integral with the upper edge of said rear wall, side walls integral with the sides of said front wall and rigidly connected to said rear wall, said top wall having a large central opening, a light pervious display member closing said opening of the top wall, a lamp socket supported by one of said side walls, a lamp carried by said socket and arranged within the sign casing to illuminate said light pervious display member, means to facilitate rigid fastening of the sign casing within a bottled goods cooling and dispensing or like cabinet, said sign casing being open at the bottom to permit the lamp to illuminate the interior of said cabinet, said rear wall of the sign casing projecting below the bottom of the latter, and a thermometer carried by said projecting lower portion of said rear wall in position to indicate the temperature within said cabinet and to be illuminated by said lamp.

4. In an automatic advertising display device of the character described, a display sign including a casing composed of a flat vertical rear wall, a forwardly and downwardly inclined top wall integral with the upper edge of said rear wall, side walls integral with the sides of said front wall and rigidly connected to said rear wall, said top wall having a large central opening, a light pervious display member closing said opening of the top wall, a lamp socket supported by one of said side walls, a lamp carried by said socket and arranged within the sign casing to illuminate said light pervious display member, means to facilitate rigid fastening of the sign casing within a bottled goods cooling and dispensing or like cabinet, said sign casing being open at the bottom to permit the lamp to illuminate the interior of said cabinet, an extension cord for placing said lamp in circuit with a source of current, and a switch interposed in said circuit in position to be mounted on the inside of the cabinet independently of the sign.
